CAN OPENER

Amos L. Maples, Long Beach, Calif.

Application October 10, 1938, Serial No. 234,149

5 Claims. (Cl. 30—10)

This invention relates to can openers.

The general object of the invention is to provide a novel can opener for opening liquid containing cans of various heights and diameters.

5 Another object of this invention is to provide a novel can opener which is adapted to provide a pouring opening on one side of the top of the can, and a vent aperture diametrically opposite thereto, in one operation on cans of various sizes.

10 Another object of this invention is to provide a can opener including a novel means whereby the can is securely clamped in place during the piercing operation.

Other objects and the advantages of my invention will be apparent from the following description taken in connection with the accompanying drawing, wherein:

Fig. 1 is a front elevation of a can opening device embodying the features of my invention;

20 Fig. 2 is a section taken on line 2—2 Fig. 1;

Fig. 3 is a section taken on line 3—3 Fig. 1;

Fig. 4 is a fragmentary section taken on line 4—4 Fig. 1;

Fig. 5 is a fragmentary section taken on line 25 5—5 Fig. 2;

Fig. 6 is a fragmentary side elevation of the can opener showing the position of the can after the handle has been depressed;

Fig. 7 is an enlarged fragmentary side elevation

30 with parts broken away showing the position of the parts in solid lines before the handle is depressed and in dotted lines after the handle is depressed;

Fig. 8 is an enlarged fragmentary section showing how the can is gripped upon depressing the handle; and

Fig. 9 is a top plan view of the plate.

Referring to the drawing by reference characters I have shown my invention as embodied in

40 a can opener which is indicated generally at 10. As shown the can opener includes a base 11 on which a pair of aligned supports 12 are secured as by rivets 13. The supports 12 include sides 14 which are fitted to the base and which are pro-

45 vided with inwardly directed annular flanges 15 arranged on the outer lower ends thereof. The upper ends of each of the flanges 15 is bevelled to form a tooth 16. The upper ends of the sides 14 are provided with integral ears 17 which are

50 apertured to receive a pin 18 which latter engages apertures in ears 19 on an arm 20 to pivotally support this arm.

The arm 20 includes a body portion 21 having sides 22 thereon and having an elongated slot 23 in which a piercing tooth member 24 is slid-

ably mounted. The tooth member 24 includes a threaded end which receives a knurled thumb nut 25 to adjustably hold the piercing pin in place.

The inner end of the body 20 is provided with a perforating member 26 which is held in place 5 by rivets 27. The member 26 includes a reinforcing rib 28 and its lower end includes a V-shaped cutting edge 29 and a piercing point 30. The outer end of the body portion 21 of the arm 20 is removed to provide portions 31 which are 10 spaced apart and which engage a handle 32 the latter being held in place by a rivet 33.

The base 11 is provided with a plurality of spaced pins 34 which are fitted in slots 35 in a 15 slidable plate 36 which includes a forwardly projecting tongue 37 notched as at 37' to provide clearance for a perforating member 26.

The arm 20 is normally urged upwardly by a coiled spring 38 which is arranged about the pin 18. The ends of the spring 38 has its free ends 20 inserted in apertures 39 in the ears 19 on the arm 20. The coil spring 38 includes an intermediate portion 40 which projects rearwardly and engages under a tongue 41 on the plate 36 to normally urge the plate upwardly.

25 Each of the ears 19 is provided with a flat surface 41' which engages the tongue 37 on the slidable plate 36. Thus this tongue 37 serves to hold the handle elevated and to limit its upward movement. The ears 19 further include inclined 30 camming surfaces 42 which engage bevelled portions 43 on the outer ends of the tongue 37 so that as the handle is swung about the pin 18 the tongue 37 is moved downwardly.

The can opening device may be attached to the 35 wall or other structure by means of screws or bolts inserted through apertures 44 provided in the base 11.

In operation the tooth 24 is spaced from the perforating cutter 26 a distance slightly less than 40 the diameter of the can to be opened. The can is then placed against the angular flanges 15 with the seam 45 of the can just above the teeth 16 as shown in solid lines in Fig. 7.

The arm 20 is then depressed causing the cam 45 surface 42 to move the plate 36 and the can downward to the position shown in dotted lines in Fig. 7. As the can is urged down by the plate 36 the teeth 16 on the upper end of the flanges 15 are forced under the seam of the can as shown 50 in Fig. 8 thereby securing the can in the proper position while the arm 20 completes its downward movement. As the motion continues the can is cut by the member 26 to provide a pouring opening and the tooth 24 punctures a vent aperture. 55

When the arm 28 reaches the position shown in Fig. 6 the handle 32 is released and the spring 38 returns the arm 28 and the plate 36 to their original position. Further upward movement of either the plate 36 or arm 28 is prevented by the flat surface 41 on the arm engaging the upper surface of the plate 36. The can may readily be removed from the opener device by a slight lifting and pulling action.

10 It will thus be apparent that I have invented a novel can opener which can be economically manufactured and which is highly efficient for the intended purpose.

Having thus described my invention I claim:

15 1. In a can opener, a base, spaced supports on said base, a handle member pivotally mounted on said supports, said supports having upwardly facing teeth thereon, a plate slidably mounted on said base, said handle including camming surfaces adapted to engage and shift said plate towards said teeth when the handle member is shifted, and a piercing member on said handle.

20 2. In a can opener, a base, a pair of spaced supports on said base, a handle member, pivot means 25 passing through said handle member and said supports, said supports having teeth on the upper ends thereof, a plate slidably mounted on said base, said handle including a portion engaging said plate to hold the handle elevated, said 30 handle including camming surfaces engaging said plate to shift said plate downwardly when said handle member is shifted, said plate being disposed above said teeth, a piercing member on said handle adjacent said pivot, said handle having a slot, and puncturing means slidably mounted in said slot.

25 3. In a can opener, a pair of spaced supports on said base, each of said supports having an ear thereon, a handle member, pivot means passing 40 through said handle member and said support ears, said support having flanges thereon, the upper end of each of said flanges being sharpened to form a tooth, a plate slidably mounted on said base, said plate including a tongue, said handle 45 ears including camming surfaces adapted to en-

gage said tongue to shift said plate downwardly when the handle member is shifted, said plate tongue being disposed above said teeth, and a piercing member on said handle adjacent said pivot.

4. In a can opener, a base, a pair of spaced supports on said base, each of said supports having an ear thereon, a handle member having ears thereon, pivot means passing through said handle member ears and said support ears, said support having flanges thereon, the upper end of each of said flanges being sharpened to form a tooth, a plate slidably mounted on said base, said plate including a tongue, said handle ears including a flat portion engaging said tongue, said handle ears including camming surfaces adapted to engage said tongue to shift said plate downwardly when the handle member is shifted, said plate tongue being disposed above said teeth, a piercing member on said handle adjacent said pivot, said handle having a slot, and puncturing means slidably mounted in said slot.

5. In a can opener, a base, a pair of spaced supports on said base, each of said supports having an ear thereon, a handle member having ears thereon, pivot means passing through said handle member ears and said support ears, said support having flanges thereon, the upper end of each of said flanges being sharpened to form a tooth, a plate slidably mounted on said base, said plate including a tongue, spring means surrounding said pivot and engaging said handle to hold the latter elevated, said spring including a portion engaging said plate to hold the latter normally raised, said handle ears each including a flat portion engaging said tongue, said handle ears including camming surfaces adapted to engage said plate tongues to shift said plate downwardly when the handle member is shifted, said plate tongue being disposed above said teeth, whereby to force a can rim against the teeth, a piercing member on said handle adjacent said pivot, said handle having a slot, and puncturing means slidably mounted in said slot.
